UNITED STATES PATENT OFFICE.

FRANK BENJAMIN HARRISON AND LACEY YEA WILLIAMS, OF TOLEDO,
OHIO.

LUBRICATING DEVICE FOR CAR-AXLE JOURNALS.

SPECIFICATION forming part of Letters Patent No. 752,163, dated February 16, 1904.

Application filed April 28, 1903. Serial No. 154,718. (No model.)

To all whom it may concern:

Be it known that we, FRANK BENJAMIN HARRISON and LACEY YEA WILLIAMS, citizens of the United States, residing at Toledo, in the county of Lucas and State of Ohio, have invented new and useful Improvements in Lubricating Devices for Car-Axle Journals, of which the following is a specification:

The object of our invention is the provision of a lubricating device for car-axle journals which shall be suspended and held by spring-pressure in contact with the lower surface of the journal.

Our invention consists in a lubricating-pan and spring devices which support the pan and are attached at their upper ends to the top of sides of the box.

It further consists in certain novelties of construction and combinations of parts hereinafter set forth and claimed.

The accompanying drawings illustrate an example of the physical embodiment of the invention with three specific spring or yielding devices for holding the pan to the journal constructed and arranged according to the best modes we have so far devised for the application of the principle.

Figure 1 is a longitudinal sectional view in elevation of the journal-box and a side view of the journal, brass, lubricating-pan, and the spring mechanism for suspending the pan. Fig. 2 is a half cross-section on line $x-x$ and a half cross-section on line $y-y$, showing the two spring or yielding devices for suspending the pan in contact with the journal and the relative locations of the several parts.

Referring to the drawings, the letter A designates the journal-box, which is of the well-known Master Car-Builders' type; B, the opening in the end closed by a lid; C, the top of the box; D, the bearing for an equalizer, the end of the frame, or a spring; E, the key; F, the brass; G, the journal; H, the lubricating-pan, which is to receive and hold the waste and lubricating material; I, the side walls of the pan; J, holes or slots in the side walls; K, a rod; L, a spring made integral with the rod or connected thereto in any

suitable manner; M, a hook which is located within the hole in the side of the pan; N, an eye; O, a hook with a threaded shank, which latter is passed through a hole in the top of the box; P, a nut on the shank; Q, a suspending-rod; R, a hook at the end engaging the hole or slot in the side of the pan; S, the threaded shank of the rod passed through a hole in the top of the box; T, a spring, and U is a nut upon the end of the shank.

It will be observed that in the two types of devices for suspending the pan (shown in full lines) the shanks of the rod Q and the hook O are located in such positions at the top of the box that they will not interfere with the equalizer or frame which rests upon the box nor with the pedestal-jaws of the truck when the box is adapted for vertical movement.

The dotted lines W W upon the pan represent the continuation of the rod K and rod Q beneath their pan and their union with the similar rods K and Q at the opposite side of the box, thus constituting a third type of suspensory means.

The method of withdrawing the pan from the box and inserting it therein is obvious from the drawings and need not be set forth.

While we have described only three examples of the yielding or spring devices for suspending the pan, we do not thereby intend to exclude from the scope of our invention other and equivalent forms of the same involving modifications, inasmuch as changes may be introduced in practice without constituting substantial departures.

What we claim as new, and desire to secure by Letters Patent, is—

1. The combination with a journal-box and journal, of a pan open at the top and closed at the bottom to contain a liquid lubricant and waste; and suspensory rods and springs secured at their lower ends to the pan and at their upper ends to the top of the box.
2. The combination with a journal and journal-box, of a lubricating-pan; a brass and wedge, there being open spaces between the edges of the brass and wedge and the sides of the journal-box; and spring suspensory means

for holding the pan against the journal; said spring suspensory means being secured at their lower ends to the pan and passed upwardly through the open spaces between the brass and wedge and the sides of the box, and secured at their upper ends to the top of the box.

In testimony whereof we affix our signatures in presence of two witnesses.

FRANK BENJAMIN HARRISON.
LACEY YEA WILLIAMS.
